UNITED STATES PATENT OFFICE.

WILLIAM HARRIS, OF NEWARK, NEW JERSEY.

SIGN-ILLUMINATOR.

1,073,346.

Specification of Letters Patent. Patented Sept. 16, 1913.

Application filed March 30, 1912. Serial No. 687,480.

To all whom it may concern:

Be it known that I, WILLIAM HARRIS, a citizen of the United States, residing at No. 597 Clinton avenue, Newark, in the county 5 of Essex and State of New Jersey, have invented certain new and useful Improvements in Sign-Illuminators, of which the following is a specification.

This invention relates to improvements in 10 sign-displaying means, and more specifically to means for illuminating the identification number of a self-propelled vehicle.

One of the objects of my invention consists 15 in providing simple, inexpensive, and efficient means for causing the identification number of a self-propelled or motor vehicle to be legible at night as well as by day, so that in the event of accident at night the vehicle in question can be easily identified by its number.

A further object of my invention consists 20 in providing a lamp box for a motor vehicle designed so as to utilize reflected light for the purpose of illuminating only the sight-25 openings for light-transmitting characters or numbers with which said casing is provided. This is the leading feature of my invention and is conducive to the attainment of marked simplicity in construction 30 and efficiency in operation of the device because the reflected rays of light will be caused to play directly upon the entire light-transmitting surfaces of the characters by which solely the motor vehicle can be identified 35 at night as well as by day. The characters exposed to the reflected rays of light will shine with a more intense luminosity than has been possible with previous structures owing to the arrangement of the reflecting 40 surfaces, and the inevitable result is a concentration of strong rays of light uniformly over the sign composed of the light-transmitting characters.

With the above and other objects in view 45 my invention consists in the combination, arrangement, and details of construction disclosed in the drawings and description, and then more particularly pointed out in the appended claims.

In the drawings Figure 1 is a top plan 50 view of my invention, with the top of the lamp box conveniently removed; Fig. 2 is a detail view of a modified mirror-carrying block to be described, Fig. 3 is a front elevation of the lamp box, Fig. 4 is a transverse 55 sectional view of my invention taken on the

line X—X of Fig. 1, one of the lamp-supporting straps being removed, Fig. 5 is a detail top plan view partly in section of the lamp supporting means and combined catch, 60 Fig. 6 is a detail view of the catch mechanism including its support and the co-operating element carried by the lamp to be secured in position, and Fig. 7 is a face elevation of the plate slotted to form a sign 65 character. Fig. 8 is a view in perspective of a mirror taken on the line y'—y' and y—y of Fig. 1.

Similar reference characters designate 70 similar parts wherever found on the drawings.

Referring to the drawings, which are merely illustrative of my invention, a casing A is composed of a top 1, bottom 2, back 3, sides 3' and a front part 4 which is hinged 75 at 5 so as to be movable to open position, the part 4 being held closed by any suitable catch such as the spring catch 6. Secured preferably in horizontal alinement at the inner surface of the front part 4 of casing 80 A are a plurality of guide members 7 each being composed of opposed grooved pieces 8 and 8' and a grooved bottom 9. Slidably disposed in said guide members and resting on the grooved bottoms thereof are glass 85 plates 10 disposed face to face against rigid plates 11 formed with slots as at 12 taking the configuration of sign characters, said glass plates 10 overlying both the sight-openings 13 formed in the hinged front part 4 90 and said rigid plates 11. These slides constitute but one contemplated form of the means for causing the light-transmitting sign characters to be interchangeably mounted upon a suitable support. For all practical purposes the front part 4 constitutes one of two oppositely-arranged members, the other member being shown as the back 3 of casing 95 A and having secured thereupon by suitable means a horizontally-extending block consisting of mirrors V-shaped in cross-section 14 and preferably wooden pieces 15 surrounding said mirrors. In Fig. 1 both the mirrors 14 and pieces 15 may be advantageously cemented to the wall 3 of casing A, but a wooden block 16, shown in Fig. 2, may be secured to said wall, having suitable sockets 17 in which are snugly fitted and cemented the mirrors V-shaped in cross-section. The mirrors 14 are of suitable size and are horizontally 100 behind the sight-openings 13 of casing A, said mirrors being inclined from 105

the vertical and sloping upwardly as at 13' so as to catch the rays of light focused upon them by the light source 19 at the desired angles to reflect the same in directions which 5 will insure that the reprojected rays fall upon the light-transmitting characters formed conjointly by the plates 10 and 11.

The light source may consist of a lamp, lantern, electric light or any other suitable 10 source of light, provision being made for focusing the rays of light in a direction opposite to that of the guide members 7, so that the rays may not directly fall upon the characters to be illuminated. The correct 15 position of the light source 19 is shown in Fig. 4, where it will be seen that the focusing annulus 20 slants as near in the direction of the reflecting faces of the mirrors 14 as may be. Supposing the light 20 source to be a lantern, the lantern will be supported upon the metallic straps or arms 21 and 22 so as to be spaced from all the walls of casing A, and so as to occupy a position in a lower plane than the guide 25 members 7 and mirrors 14. The straps 21 and 22 have offsets 23 riveted upon wall 3 of the casing A and, the straps project outwardly in converging relation therefrom, being formed at their free ends with oppositely-inclined tapering beveled recesses 30 designated 24 and 24' respectively, said recesses sloping from narrow at their rear planes to wide at their front planes, the configuration of said recesses being such that the correspondingly-shaped lugs 25 and 25' mounted 35 upon the lantern may slide readily in said recesses to be wedged thereinto as the lantern is moved forwardly. The lantern 19 has secured to its front a forwardly projecting stud or member 26 terminating in an arrow head 27 which is arranged to snap between the oppositely-arranged spring bars 28 and 28' which together are V-shaped in contour and touch each other at their free 40 ends so as to require some force to be exerted by the lamp attendant desirous of forcing them asunder. One of said spring arms, 28' is fixedly secured upon the strap 22 by an offset 23', while the other passes 45 through a relatively thin slot 29 in strap 21 and is held in proper position relatively to its mate by means both of the head 30 formed at one of its ends and the cotter pin 31 inserted through it at the inner surface 50 of strap 21, the head restraining displacement in one direction and the cotter pin in another, said cotter pin 31 being removable to cause the spring arm 28 to be slidable out of its slot so that the arrow-head 27 55 may become disengaged and move backward, when it is desired to remove the lantern. The lantern is not completely wedged home until the arrow-head protrudes forwardly of the spring-arms.

60 The principle involved in the operation of

my lamp box is simple. The angle of incidence of rays of light and the angle of reflection are always equal. The object in view is to adapt the angle of inclination of the reflecting mirrors in my device to its function of reprojecting the rays thrown upon them obliquely by the lantern or light medium 14, at the necessarily varying angles effective to illuminate the entire translucent surface of each character, and because 70 of the correct optic principle utilized the light is caused to be reflected uniformly over the entire sign composed of the numbers designated 32. The obliquity of the mirrors 14, arranged compactly in the block 75 16 is sufficient for this end and reference being made to Fig. 1 the arrangement is clearly and simply illustrated. Of course, the rays of light emanating from lantern 13 will be directed so as to fall upon the entire 80 surface of each V-shaped mirror 14, and following the course of but a single ray engaging each part of each V-shaped mirror it will be noticed that the dotted line u falling upon the guide 7' is the ray reflected by part 14^a of the mirror 14', in consequence 85 of the ray of light which had fallen directly upon the part 14^b of said mirror, whose well-known tendency to jump across to part 14^a at the correct point is thus 90 served the ray immediately being reflected from this point upon one of said interchangeable characters.

The mirrors are disposed in staggered relation relatively to the interchangeable slides, as 95 shown in Fig. 1, and owing to the fact that the reflecting surfaces 14^a and 14^b of each mirror diverge outwardly toward the slides the rays or beams of light transmitted by the lamp to said reflecting surfaces, at whatever 100 angle will be reflected in paths or pencils conducting to all of said slides, so that the light may fall uniformly upon the series of alining slides. It is obvious that the reflecting surface, 14^a or 14^b of the endmost 105 mirrors will direct the reflected light upon more than one of said slides formed by the plates 10 and 11 owing to the greater divergence of the lamp rays falling upon them, and in consequence a person looking 110 at the end characters of the identification number of an automobile, at any angle with respect to the vehicle will be able to discern them as readily as those which receive the reflected rays from the mirrors located 115 nearer to the lamp or light medium. It will be readily understood that rays may be directed by said lamp at various angles upon the opposing faces 14^a and 14^b of the mirrors 120 so that streams of light may be reflected by 125 said mirrors through the slides 8. In Fig. 1, the incident rays emanating from the lamp are designated u, v, w, x, y, and z, and the rays of reflected light are designated u', v', w', x', y', z', respectively. In a simi- 130

lar way other rays may be projected upon the effective illuminating surfaces of each slide so that the characters may be rendered very distinct.

- 5 Any number of the V-shaped mirrors may be used in connection with a corresponding number of translucent sign characters, and the angle of inclination may be varied but my underlying principle is present wherever 10 the relative positions of the mirrors, characters and lamp are those herein set forth. The front part 3 of casing A may be opened to enable the motorist to remove some slides should it be necessary to change the identification number, when traversing a foreign state or municipality at night a brilliant light will shine through the slots in the plates 11 and pass through the glass plates 10, so that the number exhibited will be 15 readily discernible even at a distance, while during daylight, the configured slots of said plates will present outlines also easily discernible.

20 Numerous modifications within the scope 25 of the appended claims may be resorted to in practice from the details of construction without departing from the principle herein disclosed.

What I desire to secure by Letters Patent is:

1. A device of the character described comprising a plurality of interchangeable characters, means for supporting said characters in alinement, a plurality of mirrors arranged in alinement, means for vertically supporting said mirrors on a level with said

characters, said mirrors being disposed in staggered relation with respect to said characters, each mirror comprising two inclined surfaces diverging toward said characters, 40 said surface being also downwardly and rearwardly inclined and a single source of light below the level of said characters and mirrors projecting its rays only in the direction of and against said mirrors. 45

2. A device of the kind described comprising spaced apart parallel members, translucent-sign portions mounted upon one of said members, a series of mirrors secured at their rear surfaces in contact with the other 50 member on a level with said sign portions, each mirror having its intermediate portion of gradually decreasing thickness from top to bottom said intermediate portion formed with faces at an angle to each other, and 55 means below the level of said characters and mirrors for projecting light upon the said mirrors.

3. A mirror consisting of a block having inclined front edges, the front of said block 60 formed with mirror faces converging inwardly from its inclined edges to a substantial median line inclined in the same direction as the front edges of said block, whereby downwardly inclined reflectors are 65 formed disposed at an angle to each other.

In testimony whereof I affix my signature in presence of two witnesses.

WILLIAM HARRIS.
